UNITED STATES PATENT OFFICE

147,317

DESIGN FOR A PHOTOGRAPHIC PRINTER OR THE LIKE

Cydney E. Breen, Los Angeles, Calif.

Application July 26, 1946, Serial No. 131,978

Term of patent 14 years

(Cl. D61—1)

To all whom it may concern:

Be it known that I, Cydney E. Breen, a citizen of the United States of America, residing in the city of Los Angeles, in the county of Los Angeles, State of California, have invented a new, original, and ornamental Design for a Photographic Printer or the like, of which the following is a specification, reference being had to the accompanying drawings, forming a part thereof.

Figure 1 is a side elevational view of a photographic printer showing my new design in an open position;

Figure 2 is a plan view of the device as shown in Figure 1;

Figure 3 is a plan view of the printer shown in Figure 1 in a closed position;

Figure 4 is a side elevational view of the device

as shown in Figure 3 and showing the side opposite that shown in Figure 1; and

Figure 5 is a rear elevational view of the printer as shown in Figure 3.

I claim:

The ornamental design for a photographic printer or the like, substantially as shown and described.

CYDNEY E. BREEN.
